(57) **CLAIM**

The ornamental design for a universal wrist splint, as shown and described.

DESCRIPTION

FIG. 1 is a perspective view of the invented universal wrist splint, showing my new design stabilizing the right wrist of a wearer, the right arm of the wearer shown in dotted lines; FIG. 2 is a perspective view of the invented universal wrist splint of FIG. 1, stabilizing the left wrist of a wearer, the left arm of the wearer shown in dotted lines;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The dotted lines are for illustrative purposes only and form no part of the claimed design.
